UNITED STATES PATENT OFFICE.

WILLIAM S. HANSON, OF CHICAGO, ILLINOIS.

GAS-ENGINE STARTER.

1,088,699.

Specification of Letters Patent.

Patented Mar. 3, 1914.

Application filed November 15, 1912. Serial No. 731,626.

To all whom it may concern:

Be it known that I, WILLIAM S. HANSON, a subject of the King of Great Britain, residing at Auburn Park, Chicago, in the county of Cook and State of Illinois, have invented certain new and useful Improvements in Gas-Engine Starters, of which the following is a specification.

This invention relates to devices for starting internal combustion engines, and has special reference to means for starting engines mounted upon automobiles, the particular object of the invention being to provide simple and efficient means whereby the chauffeur may start the engine without leaving his seat and, consequently, without running any risk of fracturing his arm or suffering other injury from the use of the ordinary crank attached directly to the engine driving shaft.

The invention seeks to provide means normally free of the driving shaft of the engine adapted to be quickly connected with said shaft, and means for readily imparting rotary motion to the shaft through said normally disconnected means.

The stated object, and other objects which will incidentally appear from the description of the invention hereinafter given, are attained in such mechanism as is illustrated in the accompanying drawings, and the invention resides in certain novel features of construction and arrangement of parts which will be particularly pointed out in the claims following the description.

In the drawings: Figure 1 is an elevation of my improved engine starting mechanism in working position with parts broken away; Fig. 2 is an end elevation of the controlling lever and the parts immediately adjacent thereto; Fig. 3 is an elevation of the actuating mechanism in normal position.

In carrying out my present invention, I secure upon the body of the automobile, at any suitable point convenient to the chauffeur's seat, a bracket 1 having a boss 2 formed thereon which constitutes a bearing for the starting shaft 3, a similar bearing 4 being provided at any convenient point of the body or frame of the vehicle. The starting shaft is slidably mounted in the said bearings and is equipped at one end with a gear wheel 5 adapted to mesh with a gear wheel 6 rigid with the driving shaft 7 of the engine. The starting shaft is normally held in such position that the gear wheel 5 will be

held away from the gear wheel 6 by a spring 8 coiled around the shaft between the fixed bearing 4 and a collar or other stop 9 rigid with the starting shaft, as will be readily understood. The end of the starting shaft remote from the gear wheel 5 extends through and beyond the lower end of a controlling or operating lever 10 which is loosely fitted to the said end of the shaft and carries a pawl 11 adapted to engage a ratchet wheel 12 so that, when the lever swings in one direction, the pawl will ride over the ratchet wheel, but, when the lever swings in the opposite direction, the pawl will engage the teeth of said wheel and thereby actuate the starting shaft, to which the ratchet wheel is fixed, and, through the intermeshing gear wheels 5 and 6, impart rotary motion to the driving shaft 7 of the engine. A latch 13 is slidably mounted on one edge of the lever 10 and is normally held in its lowered position by a spring 14 secured to the latch and to the lower portion of the lever, the lower extremity of the latch being pivotally attached to a cam 15. The said cam is pivoted to a collar 16, fitted loosely on the shaft 3, and one end of the cam engages a groove in the side of the lever, indicated at 17, while the opposite end of the cam bears against an offset or arm 18 extending from the bracket 1 and provided with a stop 19 to limit the downward movement of the said end of the cam. When the grip upon the handle 20 of the latch is released, the spring 14 will pull the latch downward and thereby move the cam so that the low part thereof will be presented to the lever and the upper portion of the offset 18. Consequently, the shaft will be moved, under the influence of the spring 8, to its normal position shown in Fig. 3.

When it is desired to start the engine, the chauffeur grasps the lever 10 and the handle 20 of the latch, thereby moving the said handle against the handle end of the lever and, consequently, raising the latch against the tension of the spring 14, as before stated. It will be readily noted that the lower end of the lever is forked and spans the ratchet wheel 12 which is fixed to the starting shaft. Consequently, when the end of the cam bearing against the lever is raised, the lever will be forced toward the bracket 1 and this lateral movement will be transmitted through the ratchet wheel to the starting shaft so that the gear wheel 5 will be caused to mesh with the gear wheel 6. The lever is then

oscillated about the end of the engine starting shaft and rotary motion imparted to the ratchet wheel 12 and the driving shaft. A few vibrations of the lever is ordinarily sufficient to start the engine and the lever is then released whereupon the parts assume their normal positions.

It will be readily noted that the device is exceedingly simple in the construction and 10 arrangement of its parts and may be easily applied to any automobile body.

A fixed guide or bearing 21 may be provided to receive the outer end of the starting shaft so as to support the same against torsional strain and the starting shaft may be extended directly from the operating lever to the driving shaft of the engine, as indicated in the drawings, or it may be in the form of a flexible shaft or otherwise constructed in members connected by gearing. The collar 16, being loose on the starting shaft, may turn about the same and also permit sliding movement thereof. The collar is thus enabled to follow the movements of the 25 operating lever and maintain its engagement therewith without any liability of distortion or breakage.

By the use of my device, the engine may be started without any necessity of the chauffeur leaving his seat and, consequently, the violent labor and danger incident to the use of the ordinary crank is entirely avoided.

What I claim is:—

1. The combination with an engine shaft, 35 of a starting shaft, a starting lever, means whereby said starting lever may rotate the starting shaft, a cam disposed to shift the starting shaft axially and thereby connect the same with the engine shaft, and means 40 carried by the starting lever to actuate said cam.

2. An engine starting device comprising in combination with an engine shaft a starting shaft, a lever mounted upon one end of

the starting shaft, means controlled by said 45 lever for rotating said shaft, a cam arranged to impart axial movement to the starting shaft to thereby connect the same to the engine shaft, means for holding the starting shaft normally disconnected from the engine shaft, a latch slidably mounted on the lever and attached to the said cam, and a spring connected with the lever and the latch to hold the cam normally in inoperative position.

3. In an engine starting device, the combination with an engine shaft of a supporting bracket having a lateral arm projecting therefrom, a stop on said arm, a starting shaft slidably journaled in said bracket, a 60 cam arranged to impart axial movement to the shaft and thereby connect the same to the engine shaft and engaging the said arm above the stop thereon, means for rotating the starting shaft, and means carried by said 65 rotating means to actuate the said cam.

4. In an engine starting device, the combination with an engine shaft of a supporting bracket, a starting shaft slidably journaled therein, a ratchet wheel fixed on said 70 shaft, a lever loosely fulcrumed on the shaft and spanning said ratchet wheel, a collar loose on the end of the shaft, a cam pivoted on said collar and engaging the bracket and the side of the lever, means carried by the 75 lever to actuate the cam and effect axial movement of the starting shaft in one direction, and means acting on the shaft to effect axial movement thereof in the opposite direction and thereby disconnect the same from 80 the engine shaft.

In testimony whereof I affix my signature in presence of two witnesses.

WILLIAM S. HANSON. [L.S.]
